FLYER FOR SPINNING MACHINES

Henry C. Herr and Harvey E. Herr, Buffalo, N. Y.,
assignors to Herr Manufacturing Company,
Inc., Buffalo, N. Y., a corporation of New York

Application July 10, 1934, Serial No. 734,472

4 Claims. (Cl. 117—26.5)

This invention relates to certain new and useful improvements in the flyers employed in connection with spinning machines.

One of its objects is the provision of a flyer of this character having an expandable journal or bearing member which is so designed and constructed as to afford a uniform and continuous bearing for the flyer irrespective of its degree of expansion occasioned by the size of the spindle to which it is attached.

Another object of the invention is to provide a balanced flyer designed to produce an even, constant and minimum thread tension, and wherein means are provided thereon for developing or creating, during the high speed motion of the flyer, a force for counter-acting the centrifugal force developed by the flyer wires.

In the accompanying drawing:—

Figure 1 is a side elevation of a bobbin and spindle showing our improved flyer operatively associated therewith. Figure 2 is an enlarged top plan view thereof. Figure 3 is a cross section taken in the plane of line 3—3, Figure 2. Figure 4 is a perspective view of the revolving portion of the flyer-body. Figure 5 is a perspective view of the journal or bearing sleeve. Figure 6 is an end view of the flyer.

Referring now to the drawing, 10 indicates a spindle of the usual tapered form, and 11 a bobbin mounted thereon. The flyer body, which is detachably mounted on the bobbin spindle, preferably consists of an anchoring sleeve or journal 12 for attachment to the tapered end of the spindle, and a substantially hollow hub or bearing composed of upper and lower cup-shaped sections 13 and 14, respectively, which may be in the form of stampings suitably fastened together by a lap or interlocking joint, and which contain bushings 15 of fiber or like material whose opposing ends terminate short of each other to provide an intervening annular space 16. The hub is free to rotate about the journal and projecting from one side of the hub is a member 17 upon which the flyer wires 18 are mounted, the same being retained in loops 19 formed in such member and a clamping ring or segment 20 being employed for detachably and securely holding the wires against displacement. In the drawing, two flyer wires are shown, one having a depending thread-engaging eye at its outer end, which, during the rotation of the flyer, assumes the outwardly-deflected position shown by full lines in Figure 1.

The anchoring sleeve or journal 12 fits comparatively loosely within the axial opening of the

hub 13, 14 and by preference is split lengthwise to provide an expandable sleeve capable of ready attachment to bobbin spindles of varying diameters. Intermediate its ends the sleeve is provided with a thrust bearing which may be in the form of an annular flange 21 which occupies the space 16 between the bushings 15 and limits the movement of the hub axially of the sleeve. As shown in Figure 3, this flange is preferably formed integrally with the sleeve by folding the sleeve upon itself. The sleeve 12 is so split as to afford under any normal expansion thereof a continuous and uninterrupted circular bearing surface for the flyer body. To this end the anchoring sleeve is split in a substantially zig-zag manner or laterally offset fashion and includes a plurality of longitudinal slit portions 22 disposed in radially different planes, and interconnected by substantially circumferentially-extending slits 23, whereby there are formed oppositely-facing tongues 24 between the longitudinal slit portions of the sleeve. These tongues, when the sleeve is expanded, span or bridge the adjoining radially offset slits and thereby provide a continuous and uninterrupted circular bearing surface for the flyer body under any normal expansion of the sleeve. The bushings 15 of the flyer body engage the journal above and below its thrust-bearing flange 21 and the circumferentially-extending slits 23, immediately adjoining such flange, are located so that they lie in planes which intersect the respective bushings, whereby upon expansion of the journal sleeve when applied to the spindle, the bushings have a continuous bearing contact with the adjoining tongues 24 of the journal across those portions thereof where gaps are present due to the expansion of the sleeve. The thrust flange 21 of the journal has a plurality of radial notches 25 which intersect the journal wall and which permit the necessary and uniform circular expansion of the journal.

Projecting from that side of the flyer-hub diametrically opposite to that of the flyer wire supporting member 17, is a member 26 which provides a means for counterbalancing the weight of the flyer wires and their attaching means when the flyer is at rest, and which is further so designed as to develop or generate a force to counteract the centrifugal force developed by the flyer wires when the flyer is in motion. For this purpose, the side portions of the member 26 at opposite sides of the radial center line thereof are reversely bent or deflected out of the horizontal to provide air-impinging surfaces 27, the air impinging against the underside of one of such

surfaces when the flyer is traveling in one direction and against the top side of the companion surface when the flyer is turning in the opposite direction. The outer end of said member 26 is 5 preferably shaped in the form of a broad V and the resulting edges thereof are curled or bent, as indicated at 28, to provide air-impacting surfaces or pockets. These pockets converge inwardly toward the center line of the member 26 and 10 terminate at the apex of the V, at which point the air directed into the pockets is centrifugally discharged. By this construction, the air directed by the deflecting surface 27 against the companion curled surface 28 exerts a pulling force or 15 thrust effect on that side of the flyer body which serves to counteract the centrifugal force developed by the flyer wires, with the result that the flyer revolves evenly and uniformly about the spindle to maintain an even tension on the 20 threads at variable speeds. Furthermore, by constructing and shaping the member 26 as described, the resistance to the rotation of the flyer is reduced to a minimum and at the same time there is accomplished the centrifugal force developed by the flyer wires.

By preference, we provide washers 29 between the opposite faces of the journal-flange 21 and the bushings 15 which afford a metal to metal contact and insures ease of operation of the flyer 30 about the journal.

We claim as our invention:—

1. A flyer for spinning machines, comprising a hub, a flyer wire projecting from one side of 35 said hub, and a member projecting from the diametrically opposite side of said hub for generating a force counter to that of the centrifugal force of the wire when the flyer is in motion, the opposite side portions of said member adjacent its outer end being reversely bent to provide air- 40 impacting surfaces.

2. A flyer for spinning machines, comprising

a hub, a flyer wire projecting from one side of said hub, and a member projecting from the diametrically opposite side of said hub for generating a force counter to that of the centrifugal force of the wire when the flyer is in motion, 5 the opposite side portions of said member adjacent its outer end being reversely bent and said member terminating at its outer edge in oppositely curled portions to provide air-impacting surfaces.

3. A flyer for spinning machines, comprising a hub, a flyer wire projecting from one side of said hub, and a member projecting from the diametrically opposite side of said hub for generating a force counter to that of the centrifugal force of the wire when the flyer is in motion, 15 the opposite side portions of said member adjacent its outer end being reversely bent and said member terminating at its outer edge and at opposite sides of its radial center line in oppositely curled portions to provide air-impacting pockets, the latter converging inwardly toward the center line of said member.

4. A flyer for spinning machines, comprising a hub, a flyer wire projecting from one side of 25 said hub, and a member projecting from the diametrically opposite side of said hub for generating a force counter to that of the centrifugal force of the wire when the flyer is in motion, the opposite side portions of said member adjacent 30 its outer end being reversely bent out of a horizontal plane and the outer end of said member having a substantially V-shaped notch therein, the edges forming said notch being curled in opposite directions, respectively, to form air-impacting pockets, the latter converging inwardly and the apex of the notch forming an outlet for the displacement of the air.
